APPARATUS FOR AND THE METHOD OF
TREATING FIBROUS WASTE FOR JOUR-
NAL BOX USEEdwin S. Pearce, Indianapolis, Ind., assignor to
Railway Service & Supply Corporation, Indian-
apolis, Ind., a corporation of Indiana

Application January 22, 1934, Serial No. 707,698

16 Claims. (Cl. 141—2)

This invention relates to apparatus for and the method of treating fibrous waste for journal box use, the invention relating to the treatment of both new waste and old waste.

5 In the manufacture of waste and in the use of waste, very small fragments of the wool or cotton fibres of which the waste is made are produced, said fragments being known as lint. The presence of this lint in waste materially 10 reduces its effectiveness as a carrier of lubricating oil, and its removal is therefore highly desirable if not actually essential. Likewise, in both new and used waste, particularly in the latter, there is usually more or less moisture, 15 the presence of which in waste is highly objectionable because of its emulsion-forming properties. Furthermore, old waste contains more or less dirt, cinders, bits of metal, etc., as the result of its use in journal boxes, and more or less 20 dirty journal oil in a more or less viscous state.

It is therefore quite essential, in the proper treatment of new waste, to remove therefrom the lint and moisture thereof, and in the proper treatment of used waste, to remove therefrom 25 its lint, moisture, dirt, bits of metal, etc., and as much of its dirty oil as possible.

The present invention therefore has for its general object the provision of an improved apparatus for and an improved method of treating such fibrous waste, both new and old, to effectively and efficiently remove therefrom substantially all of its objectionable content, including 30 lint, moisture, dirt, bits of metal, etc., and dirty oil.

35 A more specific object of the present invention is the provision of improved waste treating apparatus in the form of a single simple and inexpensive machine, with which are performed all of the steps of the present improved method, 40 said method requiring for its performance a minimum handling of the waste and minimum amounts of time and labor.

45 Further objects of the present invention are in part obvious and in part will appear more in detail hereinafter.

The invention will be readily understood from the following description thereof, reference being had to the accompanying drawings in which

50 Fig. 1 is a central vertical sectional view of the machine constituting the present improved waste treating apparatus, the waste-receiving container of said machine being shown in its lowered, rotatable position; Fig. 2 is a side elevation of said machine, with a part of the cas-

ing thereof broken away to show said waste-receiving container in its raised, non-rotatable position; and Fig. 3 is a detail vertical sectional view of the operator-controlled mechanism for effecting raising and lowering of said waste-receiving container, the plane of said view being at right angles to the plane of Fig. 1.

In the embodiment of the invention here illustrated, 10 represents the generally cylindrical casing of the machine, said casing being mounted upon suitable legs 11 to provide space therebeneath for a part of the hereinafter described spindle rotating means. With the exception of a bottom liquid-discharge opening 12, with which 15 communicates a valve-controlled discharge pipe 13, said casing is of imperforate character and therefore capable of receiving and holding a treating liquid, such as lubricating oil. To heat the treating liquid supplied thereto and/or to maintain said liquid in a heated condition, said 20 casing is preferably provided with suitable heating means, the means here shown comprising steam coils 16 suitably arranged around the inner surface of said container.

25 Centrally mounted in the base of said casing is a suitable bearing assembly 20, in which is rotatably mounted a vertically disposed spindle 22. On the lower end portion of said spindle, which end projects below the bearing assembly 20 and the base of said casing, is suitably secured a pulley 25 adapted to be driven, through the instrumentality of one or more belts (not shown), by an electric motor or other suitable power means (also not shown).

30 On an intermediate portion of said spindle, just above the bearing assembly 20, is secured a suitable screw propeller 27, said propeller being secured to said spindle for rotation therewith at all times. Suitably mounted on the upper end portion of said spindle, which end portion 35 lies within the casing 10, is a generally cylindrical waste-receiving basket or container, said container being so mounted on said spindle that it rotates therewith only when actually connected thereto. For effecting such connection of said 40 container to said spindle, suitably operator-controlled means is provided, the construction of which will be later described.

45 The waste-receiving container here shown includes a perforated bottom wall 38 and a perforated side or peripheral wall 31, the perforations of said walls being in the form of relatively small, closely spaced apertures through which may freely pass the oil or other treating liquid, 50 55

- and all objectionable content of the waste transferred thereto, such as lint, dirt, bits of metal, etc. Suitably mounted in a centrally disposed opening 32, with which the container bottom 5 wall 30 is provided, is a vertically disposed hub portion 34, the elongated chamber of which constitutes a suitable socket 35 for the reception of the upper end portion of the spindle 22, as shown.
- 10 The cover of this waste-receiving container is in two parts, there being a marginal portion 36, of annular form and of imperforate character, welded or otherwise suitably secured to the upper edge portion of the container side wall 31, and a 15 central portion 37, of circular form and of perforate character, bolted or otherwise suitably secured at 40 in spaced relation to an imperforate cover 42 with which the casing 10 is provided, said casing cover being hingedly mounted so that 20 it may be readily swung upwardly to one side during loading and unloading of the container with waste and during the step of supplying the casing 10 with a treating liquid.

The means for detachably connecting the 25 waste-receiving container to the spindle 22, for rotation therewith, may be of any suitable form. As here shown, said means includes a vertically disposed eccentric disc 45 carried by and rotatable between a pair of apertured ears 46 with which 30 the upper end of the hub portion 34 of said container is provided, such mounting of said disc being effected by means of a cross pin 47 extending through and suitably secured to said disc, such as by a set screw 48, and having its projecting end 35 portions extending through the apertures of said ears.

By connecting said disc to the spindle 22, a connection here effected by the use of a locking screw 50, as shown in Fig. 1, the waste-receiving 40 container is caused to rotate with said spindle, as will be readily understood. To disconnect said disc from said spindle, and thereby permit said container to remain stationary during rotation of said spindle, it is merely necessary to withdraw 45 said locking screw 50 from its threaded connection with said spindle, as likewise will be readily understood.

Suitably mounted on the upper end of said spindle 22, such as in a marginally disposed annular groove, is a suitable thrust bearing 54, on 50 which said eccentric disc 45 rests when disconnected from said spindle, as shown in Fig. 2. During such periods of disconnection, the locking screw 50 of said disc lies within a diametrically 55 disposed passageway 55 with which said disc is provided, said locking screw being prevented from escaping from said passageway by a suitable washer-like abutment 56 secured at the outer end of the enlarged portion of said passageway, as shown.

The function of the propeller 27, as will later appear, is to effect a forcible passage of two treating 65 mediums up through the perforated bottom wall 30 of the waste-receiving container and thence upwardly through the waste therein. In practicing the present method, hereinafter more fully described, hot lubricating oil is first forcibly passed upwardly through said waste, with consequent agitation thereof and transfer to said oil of an appreciable portion of the objectionable 70 content of said waste. After removal of said oil and the objectionable content of the waste transferred thereto, currents of heated air are passed upwardly through said waste, the effect of which

is to open up the waste fibres, etc., and to vaporize any moisture remaining in the waste.

To assist the propeller 27 in effecting such passage of lubricating oil and air upwardly through the perforated bottom wall 30 of said container and thence through the waste therein, a suitable baffle plate 60 is provided for cooperation with said propeller. As here shown, said baffle plate is of generally inverted, frusto-conical shape, being arranged in surrounding relation 10 relative to said propeller and having its upper enlarged end portion suitably secured to two or more circumferentially disposed brackets 62 with which the casing 10 is provided. The opening at the lower and smaller end of said baffle plate has 15 a diameter slightly less than that of the propeller 27, and the opening at the upper and larger end of said baffle plate has a diameter slightly greater than that of the waste-receiving container, as clearly shown in Figs. 1 and 2. 20

To prevent the passage of oil and air, as the result of rotation of the propeller 27, upwardly through the annular space 64 between the lower end of the container side wall 31 and the upper end of the baffle plate 60, said lower end of said baffle plate are provided with cooperating annular sealing strips 65, inter-engagement of which is effected by upward movement of said container. To effect such upward container movement, it is 30 merely necessary to turn the eccentric disc 45 ninety degrees, from the position shown in Fig. 1 to the position shown in Fig. 2, and this may be conveniently accomplished by imparting the desired rotary movement to either one of the two 35 projecting ends of the cross pin 47, which pin is secured to said eccentric disc by the set screw 48.

As here shown, each of the two projecting ends of said cross pin 47 is provided with a suitable socket 67 to removably receive a hex wrench or 40 the like, by the use of which the desired rotary movement can be readily imparted to said pin. In a similar manner, the head of the locking screw 50 is provided, with a suitable wrench-receiving socket 68, to enable said screw to be 45 readily moved inwardly or outwardly, depending upon whether it is to be connected to the spindle 22 or disconnected therefrom.

When the waste-receiving container is in its raised position, as shown in Fig. 2, it is free of 50 operative connection with the spindle 22 and therefore does not rotate therewith. This is the position of said container during the steps of passing oil, and later air, upwardly through the waste in said container, said waste because of its 55 stationary condition, being free of any compressing or matting effects thereon. In this raised position of the waste-receiving container, the annular space 64 between the lower end thereof and the upper end of the baffle plate 60 is securely 60 closed by the inter-engaging sealing strips 65, so that the oil and the air forced upwardly by rotation of the propeller 27 are compelled to pass through the perforated bottom wall 30 of the waste-receiving container and thence upwardly 65 through the waste therein.

Inasmuch as the propeller 27 recirculates the oil through said waste, the extent of such recirculation depending upon the condition of cleanliness of the waste being treated, it is quite advisable to remove from the circulating oil as rapidly 70 as possible and as much as possible of the objectionable content of the waste transferred thereto. Although the lint transferred to the oil cannot be removed therefrom by filtering means, as 75

pointed out in one or more of my prior patents for treating or conditioning waste, dirt, cinders, bits of metal, etc., to a greater or lesser extent, can be removed therefrom in that way, and in the present embodiment of the invention, an annular perforated filter plate 10 is horizontally arranged at the upper end of the waste-receiving container, in bridging or spanning relation relative to the annular space 12 between the side wall 10 of the waste-receiving container and the side wall of the surrounding casing 10. As here shown, said plate is mounted upon suitable circumferentially disposed brackets 14 with which said casing is provided, and bolted or otherwise suitably secured to the inner edge portion of said plate is an annular sealing strip 76 for yieldingly engaging the container cover portion 36 when said container is in raised position, as shown in Fig. 2.

In practicing the improved method of the present application, the casing 10 is supplied with a proper quantity of lubricating oil, either new oil or reclaimed oil, and preferably in a heated condition, the oil being supplied to said casing by the use of any suitable means, such as a supply hose or the like. The casing is preferably filled with oil to a point just below the brackets 14 on which is mounted the filter screen 10, and if the oil delivered to the casing is in an unheated condition, sufficient time should be given the steam coils 16 to effect proper heating of said oil before treatment of the waste therewith begins. Usually, the oil delivered to the casing 10 is in a heated condition and the steam pipes 16 therefore function merely as a means for maintaining the oil in such condition.

After supplying the casing with lubricating oil, and with said oil in a heated condition, the waste to be treated is placed in the container provided therefor, said container being in its raised position, as shown in Fig. 2, and hence being free of operative connection with the spindle 22.

The next step in the present improved method is to effect rotation of the propeller 27, and this is accomplished by rotating the spindle 22 on which said propeller is rigidly mounted. Such rotation of said propeller effects a forcible passage of said hot lubricating oil upwardly through the perforated bottom wall 30 of said container and thence upwardly through the waste therein, said waste being violently agitated in said oil, with consequent transfer to said oil of an appreciable portion of the objectionable content of said waste. Due to the use of the sealing strips 65 and the baffle plate 60, all of the oil forced upwardly by rotation of the propeller 27 is compelled to pass through said container and hence through the waste therein, as will be readily understood. After passing upwardly through said container and said waste, the oil flows outwardly onto the filter screen 10, which screen collects an appreciable portion of the dirt, cinders, bits of metal, etc., transferred to said oil from the waste. The filtered oil passes down through said screen into the annular space 58 between the container and casing side walls and thence back into the bottom of the casing and such circulation of said oil, effected by rotation of the propeller 27, is continued as long as desired, the condition of cleanliness of the waste largely determining the duration of this oil flushing operation.

The next step in the present improved method, after stopping the rotation of the spindle 22 and hence that of the propeller 27, is to effect the

removal from the casing 10 of as much as possible of said treating oil. Due to the location of the discharge opening 12, the oil readily drains by gravity from said casing, said oil flowing therefrom through the now open discharge pipe 13 to a storage reservoir, an oil reclamation plant or to any other device or apparatus, as desired.

After removal of such oil from the casing 10, the operator lowers the waste-receiving container and by the use of the screw 50 operatively connects it to the spindle 22 for rotation therewith. Rotation of said spindle is then effected, with consequent rotation of the waste container and the discharge from said waste of a very appreciable portion of the treating oil therein, the oil removed from said waste flowing out of the casing 10 through the outlet opening 12 and the discharge pipe 13.

After such removal from said waste of as much as possible of said treating liquid, the waste is subjected to the drying and resiliency-restoring effects of heated air currents. For this part of the method, the waste container is freed of its operative connection with said spindle 22 and is raised by means of the eccentric disc 45 to the position shown in Fig. 2. Rotation of the spindle 22 is again initiated, with consequent rotation of the propeller 27 and the forcible passage through the container and the waste therein of heated air currents, the effect of which is to vaporize any moisture remaining in the waste and to open up the waste fibres. The air currents are heated, of course, by the steam coils 16, and if rotation of the container in the preceding oil-removing step has resulted in packing or compressing the waste against the side wall of said container, said waste may be pulled down therefrom so that the passage of the air therethrough can be more effective.

It is to be understood, of course, that the oil and air treating steps may be repeated, if desired, the advisability of so doing depending upon the condition of the waste being treated. Likewise, the waste may be treated, before being removed from the present apparatus, with other mediums than the two here mentioned.

If desired, the waste may be supplied with a proper quantity of lubricating oil, for journal box use, before being removed from the present apparatus, said oil being added to the waste, either while said container is stationary or while it is rotating.

Further features and advantages of the present improved apparatus and the present improved method will be apparent to those skilled in the art to which it relates.

What I claim is:

1. Apparatus for treating fibrous waste for journal box use, comprising a casing for receiving and holding a treating liquid, means within said casing for heating the liquid therein, a perforated rotatable container mounted in said casing for receiving and holding the waste to be treated, means in said casing and outside of said container for effecting a forcible passage of said treating liquid through said container and hence through said waste, with consequent transfer to said liquid of at least some of the objectionable content of said waste, means for effecting the removal from said casing of the major portion of said treating liquid, and means for rotating said container to remove from said waste an appreciable portion of the treating liquid therein.

2. Apparatus for treating fibrous waste for journal box use, comprising a casing for receiv-

- ing and holding a treating liquid, a perforated rotatable container mounted in said casing for receiving and holding the waste to be treated, means arranged between said casing and said container for heating the liquid in said casing, means arranged between said casing and said container for effecting a forcible passage of said treating liquid through said container and hence through said waste, with consequent transfer to said liquid of at least some of the objectionable content of said waste, means for effecting the removal from said casing of the major portion of said treating liquid, and means for rotating said container to remove from said waste an appreciable portion of the treating liquid therein.
3. Apparatus for treating fibrous waste for journal box use, comprising a casing for receiving and holding a treating liquid, a rotatable container mounted in said casing for receiving and holding the waste to be treated having a bottom wall perforated throughout substantially its entire area, means arranged below said container bottom wall for effecting a forcible passage of said treating liquid upwardly through substantially the entire perforated area thereof and thence through said waste, with consequent transfer to said liquid of at least some of the objectionable content of said waste, means for effecting the removal from said casing of the major portion of said treating liquid, and means for rotating said container to remove from said waste an appreciable portion of the treating liquid therein.
4. Apparatus for treating fibrous waste for journal box use, comprising a normally imperforate casing, a waste-receiving container arranged within said casing and having a perforated bottom wall, propeller means arranged within said casing beneath said container for effecting a forcible passage of a treating fluid through said perforated container wall and thence through the waste in said container, and a generally annular baffle plate carried by said casing and cooperating with said propeller means in effecting such forcible fluid passage through said container and said waste, the opening of said baffle plate at the upper end thereof being of greater cross dimensional size than said container.
5. Apparatus for treating fibrous waste for journal box use, comprising a casing for receiving and holding a treating liquid, a waste-receiving container rotatably mounted in said casing and having a perforated bottom wall, means arranged within said casing, beneath said container, for effecting a circulation of said treating liquid through said perforated container wall and thence through the waste in said container, and means within said casing for subjecting said liquid to a cleansing effect during such circulation.
6. Apparatus for treating fibrous waste for journal box use, comprising a casing for receiving and holding a treating liquid, a waste-receiving container rotatably mounted in said casing and having a perforated bottom wall, means arranged within said casing, beneath said container, for effecting a circulation of said treating liquid through said perforated container wall and thence through the waste in said container, and filter means arranged between said container and said casing for subjecting said liquid to a cleansing effect during such circulation.
7. Apparatus for treating fibrous waste for journal box use, comprising a liquid receiving casing, a waste-receiving container arranged within said casing and having a perforated bottom wall, propeller means arranged in said casing beneath said container for effecting a circulation of said treating liquid through said perforated container wall and thence through the waste in said container, and means for rotating said container to remove from said waste an appreciable portion of the treating liquid.
8. The method of treating fibrous waste for journal box use, comprising the step of placing the waste to be treated in a perforated container arranged in a liquid-containing casing; the step of thereafter effecting, while said container is stationary in said casing, a forcible passage of said treating liquid upwardly throughout substantially the entire area of the bottom wall of said container and hence through said waste therein; the step of thereafter removing from said casing, while said container is stationary therein, at least the major portion of said treating liquids; and the step of thereafter rotating said container in said casing to effect the removal from said waste of an appreciable portion of the treating liquid therein.
9. The method of treating fibrous waste for journal box use, comprising the step of placing the waste to be treated in a perforated container mounted in a liquid-containing casing; the step of thereafter effecting, while said container is stationary in said casing, a forcible passage of said treating liquid upwardly throughout substantially the entire area of the bottom wall of said container and hence through said waste; the step of thereafter removing from said casing, while said container is stationary therein, at least the major portion of said treating liquid; the step of thereafter rotating said container in said casing to effect the removal from said waste of an appreciable portion of the treating liquid therein; and the step of thereafter effecting, while said container is in said casing and while said waste is not subjected to an appreciable packing or compressing effect, the forcible passage of air upwardly through said container and hence through said waste.
10. Apparatus for treating the fibrous waste for journal box use, comprising a casing for receiving and holding a treating liquid, a perforated container mounted in said casing for receiving and holding the waste to be treated, means for moving said container in said casing between an upper stationary position and a lower rotatable position, a perforated cover for said container engaged thereby when said container is in its upper stationary position, means for effecting, when said container is in its upper stationary position, a forcible passage of the treating liquid in said casing through said container and thence through said waste, with consequent transfer to said liquid of at least some of the objectionable content of said waste, means for enabling the major portion of said treating liquid to be removed from said casing, and means for effecting rotation of said container, when it is in its lower rotatable position, to remove from said waste an appreciable portion of the treating liquid therein.
11. Apparatus for treating fibrous waste for journal box use, comprising a casing for receiving and holding a treating liquid, an imperforate cover for said casing, a perforated container

- mounted in said casing for receiving and holding the waste to be treated, means for moving said container in said casing between an upper stationary position and a lower rotatable position, 5 a perforated cover for said container carried by said casing cover and engaged by said container when said container is in its upper stationary position, means for effecting, when said container is in its upper stationary position, a forcible passage of the treating liquid in said casing through said container and thence through said waste, with consequent transfer to said liquid of at least some of the objectionable content of 10 said waste, means for enabling the major portion of said treating liquid to be removed from said casing, and means for effecting rotation of said container, when it is in its lower rotatable position, to remove from said waste an appreciable portion of the treating liquid therein.
- 20 12. Apparatus for treating fibrous waste for journal box use, comprising a casing for receiving and holding a treating liquid, a vertically disposed spindle structure rotatably mounted in said casing, a perforated waste receiving container loosely mounted on said spindle structure in said casing, and means for releasably connecting said container to said spindle structure for rotation therewith, said means including a vertically disposed rotatable disc eccentrically 25 mounted on said container and adapted to be releasably connected to said spindle structure, the eccentric mounting of said disc enabling said container to be raised and lowered relative to said spindle by rotary movement of said disc.
- 30 13. Apparatus for treating fibrous waste for journal box use, comprising a generally cylindrical casing for receiving and holding a treating liquid, a generally cylindrical perforated container mounted in said casing for receiving and holding the waste to be treated, said container being of such size that a generally annular space 35 is provided between the side wall thereof and the side wall of said casing, means for vertically moving said container in said casing between an upper position and a lower position, means for rotating said container when it is in its lower position, means for effecting a flow of liquid in said casing when said container is in its upper position, and liquid baffle means in said annular space for engagement by said container when said container is in its upper position, with consequent restriction of the flow of treating liquid through said annular space when said container is in its upper position.
- 40 14. Apparatus for treating fibrous waste for journal box use, comprising a generally cylindrical casing for receiving and holding a treating liquid, a generally cylindrical perforated container mounted in said casing for receiving and holding the waste to be treated, said container being of such size that a generally annular space 45 is provided between the side wall thereof and the side wall of said casing, means for vertically moving said container in said casing between an upper position and a lower position, means for rotating said container when it is in its lower position, means for effecting a flow of liquid in said casing when said container is in its upper position, and liquid baffle means in said annular space for engagement by said container when said container is in its upper position, with consequent restriction of the flow of treating liquid through said annular space when said container is in its upper position.
- 50 15. Apparatus for treating fibrous waste for journal box use, comprising a casing for receiving and holding a treating liquid, a container mounted in said casing for receiving and holding the waste to be treated, said container having a perforated bottom wall, and being of such size that a generally annular space is provided 55 between the side wall thereof and the side wall of said casing, means for vertically moving said container in said casing between an upper position and a lower position, means for rotating said container when it is in its lower position, means for arranging within said casing below said container for effecting when said container is in its upper position, a forcible passage of said liquid upwardly through the perforated bottom wall of said container and through the waste therein, a generally annular deflector surrounding said last named means and cooperating therewith in effecting the forcible passage of said liquid through the perforated bottom wall of said container, said deflector being of such size at its 60 upper end that a generally annular space is provided between said end and said container, and liquid baffle means carried by said deflector upper end for baffling the space between said end and said container when said container is in its upper position.
- 55 16. Apparatus for treating fibrous waste for journal box use, comprising a casing for receiving and holding a treating oil, a perforated container mounted in said casing for receiving and holding the waste to be treated by such oil, the side wall of said container being spaced from the side wall of said casing with the consequent provision of an annular space therebetween, means arranged within said casing below said container for effecting a flow of such oil through and around said container and through the waste therein, and heating coils for said treating oil arranged in vertical series in the annular space between the side walls of said casing and said container, with consequent restriction of the flow of oil through such space and the effective heating of such oil, thereby insuring sufficient mobility of such oil to enable it to properly flow through the waste in such container.

EDWIN S. PEARCE.
